F. MANKEY.

PANEL.

No. 16,297.

Patented Sept. 29, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,297, dated September 29, 1885.

Application filed August 13, 1885. Term of patent 7 years.

To all whom it may concern:

Be it known that I, FREDERICK MANKEY, of Williamsport, Lycoming county, Pennsylvania, have invented and produced a new and original Design for Panels, reference being had to the accompanying photographs, forming parts hereof.

Figure 1 represents a panel of my new design. Fig. 2 is a panel composed of four smaller panels, substantially similar to Fig. 1.

My design consists in a series of elevations, A, extending diagonally across the panel. The upper surfaces of said elevations A are curved or rounded. Between said elevations are broad channels or spaces B. The elevations A lie in a direction diagonal or at an angle to the natural grain of the panel. Upon the surfaces of said elevations is a different marking of the grain from that which appears on the flat parts of the panel.

The elevations A may be disposed diagonally to the grain in either direction.

In Fig. 2 I show four panels, each having

the design represented in Fig. 1, and united to produce a panel on which appear four sets 25 of chevrons, as C, D, E, and F.

I claim—

1. The design for a panel, substantially as herein shown and described, which consists in the diagonally-disposed elevations A, having 30 rounded upper surfaces, and the intermediate channels, B, the surfaces of said elevations showing a different marking of the grain of the material of the panel from that appearing in the channels.

2. The design for a panel, substantially as herein shown and described, which consists in the four series of raised chevrons C D E F, with intermediate channels, B, the said chevrons having rounded upper surfaces and the 40 said surfaces showing a different grain-marking from that appearing in the channels.

FREDERICK MANKEY.
